[57] CLAIM

The ornamental design for a compartmented bag, substantially as shown and described.

DESCRIPTION

FIG. 1 is a side elevational view of a compartmented bag showing my new design, the opposite side being a mirror image thereof;

FIG. 2 is an end elevational view thereof;

FIG. 3 is a side elevational view in a filled condition, with the top portion tied to prevent leakage; and

FIG. 4 is an end elevational view thereof.

The dash lines in the drawings represent score lines.
